UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed March 8, 1921. Serial No. 450,737.

To all whom it may concern:

Be it known that I, FRED S. CARR, a citizen of the United States, and a resident of Newton, in the county of Middlesex, Commonwealth of Massachusetts, have invented an Improvement in Separable Fasteners, of which the following description, in connection with the accompanying drawings, is a specification, like characters on the drawings representing like parts.

This invention pertains to improvements in separable fasteners. It is among the objects of the invention to provide a superior separable fastener of simple and inexpensive construction.

In the drawings, which show a preferred embodiment of one form of my invention:—

Figure 1 is a front elevation of two pieces of fabric carrying the stud and socket members, the latter being shown in dotted lines;

Fig. 2 is a section on the line 2—2 of Fig. 1, being partly in elevation;

Fig. 3 is a front elevation of the socket member; and

Fig. 4 is a front elevation of the stud.

Referring to the drawings and to the preferred form of my invention selected for illustrative purposes, I have shown a stud of conventional form including a base 5, a head 6 and a neck 7. The stud may be secured to its carrying fabric 8 in any suitable way, as by stitching 9.

The preferred form of socket member illustrated does not include any casing, but is formed of a single piece of wire bent to provide the stud-receiving aperture 10 and to provide loop portions 11, lending resiliency to the socket and inculuding, adjacent the ends of the wire which forms the socket, adjacent eyes 12, 12 adapted to be sewn together when the socket is stitched to its carrying fabric 13 so that the resiliency of the socket will be rather evenly distributed around the same with no substantial tendency to increased spreading movement at that side of the socket where the ends of the wire are located. The loops 11 are preferably three in number, symmetrically disposed about the aperture, preferably about 90° apart as shown, and each is of a diameter approximating or even exceeding that of the aperture. The result is that the socket is quite resilient and spreads symmetrically when the stud is pressed into the

aperture. This symmetrical spreading also reduces strain on the stitching.

The socket illustrated is very thin, and is preferably substantially flat.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

1. A fastener socket formed of a single piece of wire providing a plurality of resilient loops arranged about a stud-receiving aperture, and also having two stitch-receiving eyes, the two stitch-receiving eyes being adjacent each other and spaced from the stud-receiving aperture by the end portions of the wire, said end portions being of sufficient length so that the aperture may spread or expand substantially symmetricaly when the stud is forced thereinto without putting an undue strain on the stitches which pass through said eyes and secure the socket to the carrying fabric.

2. A fastener socket formed of a single piece of wire providing a plurality of resilient loops about a stud-receiving aperture and two stitch-receiving openings, one adjacent each end of the wire forming the socket, said stitch-receiving openings in adjacency to each other whereby a portion of the stitching securing said socket to its carrying fabric may hold in adjacency the terminal portions of the wire and tend to equalize the resiliency of the cooperating portions of said socket, said socket presenting two resilient wire portions between said stitch-receiving openings and said stud-receiving aperture.

3. A socket for separable fasteners formed of a single piece of wire and providing a stud-receiving aperture and a plurality of loops arranged about said aperture, said loops substantially closed to prevent entrance of the neck of the cooperating stud into said loops, and the end portions of said wire brought into adjacency and looped to provide stitch-receiving openings, said plurality of loops each approximating in diameter the diameter of said stud-receiving aperture.

4. A separable fastener comprising, in

combination, a stud having a head, a neck and a base portion, a socket formed of a single piece of wire and providing a stud-receiving aperture, the terminal portions of the wire forming said socket being looped to provide adjacent stitch-receiving apertures, said wire also providing loops about said stud-receiving aperture, and said wire providing adjacent said loops and adjacent 10 said terminal portions angular corners wherein the neck of said stud may enter under lateral strain, the wire forming the socket being arched to oppose distortion thereof beyond its elastic limit when said 15 stud and socket are under lateral strain.

5. A fastener socket formed of a single piece of wire, bent to lie in a single plane

and provided with three resilient substantially closed loops, the ends of said wire extending outwardly from the stud-receiving aperture and terminating in stitch-receiving eyes, the terminals of the wire and the three loops being disposed substantially 90° apart and being symmetrically arranged relative to a central stud-receiving aperture provided by the wire, whereby a socket member is provided whose stud-receiving aperture spreads symmetrically under pressure from the stud without undue strain on the stitching which holds the socket member to the fabric. 20 25 30

In testimony whereof, I have signed my name to this specification.

FRED S. CARR.
